UNITED STATES PATENT OFFICE

169,673

BRUSH OR SIMILAR ARTICLE

Bert Horton, New York, N. Y.

Application July 11, 1951, Serial No. 15,826

Term of patent 7 years

(Cl. D9—2)

To all whom it may concern:

Be it known that I, Bert Horton, a citizen of the United States of America, residing in the Borough of Manhattan, city, county, and State of New York, have invented a new, original, and ornamental Design for a Brush or Similar Article, of which the following is a specification, reference being had to the accompanying drawings, forming part thereof, wherein:

Figure 1 is a front elevation of a brush embodying my new design;

Figure 2 is a side elevational view of the brush shown in Figure 1, both sides being the same;

Figure 3 is a cross-section of a brush shown in Fig. 1, taken on the line 3—3 of Fig. 1; and

Figure 4 is a plan view of the brush of Fig. 1.

The dominant feature of my design resides in the portions shown in full lines.

I claim:

The ornamental design for a brush or similar article, as shown and described.

BERT HORTON.
